(74) Attorney, Agent, or Firm—Banner & Witcoff, Ltd.

(57)

CLAIM

The ornamental design for a watch, as shown and described.

DESCRIPTION

FIG. 1 is a front elevation of a watch showing our new design; and,

FIG. 2 is a front and right side perspective view thereof.

The broken line showing of various regions and the unshaded areas therein are for illustrative purposes only and form no part of the claimed design.
